UNITED STATES PATENT OFFICE.

GEORGE HENRY WHEARY, OF RACINE, WISCONSIN, ASSIGNOR TO WHEARY TRUNK COMPANY, OF RACINE, WISCONSIN, A CORPORATION OF WISCONSIN.

BAGGAGE CARRIER.

Application filed February 28, 1927. Serial No. 171,596.

This invention relates to certain new and useful improvements in baggage carriers and refers more particularly to a wardrobe trunk of the suit case type similar to that illustrated in my co-pending application, Serial No. 171,594.

This invention contemplates as one of its objects the provision of an improved suit case type wardrobe baggage carrier which will have all the exterior appearances of a suit case and which will be of light weight but of strong and durable construction.

A further object of this invention resides in an improved baggage carrier of the character described having an extension member projected from the bottom portion of its main section to form a well or space over which a removable receptacle or container is mounted, the closure for the case moving over the extension and receptacle.

And a still further object of this invention resides in the provision of an improved baggage carrier of the character described in which a box-like extension member is rigidly connected with a main section at its bottom and projects therebeyond to fit within the closure and into which the lower ends of garments hung from hangers at the upper end of the main section may extend.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view of a baggage carrier embodying my invention illustrating the same as closed;

Figure 2 is a perspective view thereof in open position;

Figure 3 is an enlarged, fragmentary view of the lower portion of the carrier and taken vertically through Figure 2 on the plane of the line 3-3, and

Figure 4 is a view taken transversely

through Figure 3 on the plane of the line 4-4.

Referring now more particularly to the accompanying drawing in which like numerals designate like parts throughout the several views, the numeral 5 designates a case or main section provided with an enclosure or cover 6 which is hinged thereto along one marginal edge and is secured in closed position by suitable hasps 7 and a key actuated lock 8. The over-all dimensions of the carrier when closed are preferably such as to permit its being positioned under a standard Pullman car seat and two handles or grips 9 and 10 are mounted on one side and top respectively thereof to permit its being handled in the manner of a suit case or else upright in the manner of a wardrobe trunk.

The structure so far described is substantially conventional with the exception of the handle 10 and this invention contemplates the provision of a novel interior construction and reinforcement whereby garments may be hung within the case 5 from suitable hangers 11 to lie within the interior 12 thereof and at the same time the case may be used as a conventional suit case to permit access to various articles, not shown, in a receptacle or container 13 removably mounted in the front portion of the case 5 outwardly of the garments, not shown, supported from the hangers 11. The hangers 11 are of conventional construction and are supported from trolleys 14 secured in the case at its upper end and having extensions 15 which function in the conventional manner to permit the separating or spreading of the hangers 11 to facilitate the removal of any one garment without disturbing the others.

The receptacle 13 has a closure or lid 16 hinged thereto which is secured closed by suitable catch means fragmentarily illustrated in Figure 2 as at 17, and is of a width to fit within the case 5 and of a height to extend from a point close to the trolley down to a point spaced from the bottom of the case. The receptacle is removably secured in the case by trunnions 18 projected from its sides adjacent its top and bottom and engageable in notches or recesses in supporting hooks 19 carried by side angle pieces 20 secured along the front marginal edges of the case side panels, in the manner best illustrated in my application aforementioned.

The bottom of the container or receptacle

13 is preferably spaced from the bottom of the case and this space is filled by an extension member 21 of a width substantially equal to the width of the case 5 and of a height to 5 fill the space beneath the receptacle or container, the upper panel or wall of the extension being in substantially vertical alignment with that of the container. The extension 21 consists of front and side panels 22 10 and 23, respectively, and a bottom 24 and its inner end extends into the case and is secured therein by rivets or other means 25. If desired, the case is reinforced at its bottom by bracing strips 26 extending about the inner 15 portion of the extension member and secured in place by the rivets 25, the strips 26 also serving to provide a clearance 27 between the extension member and the closure 6 to eliminate the necessity of extreme accuracy in 20 manufacture.

If desired, the container or receptacle may extend into the extension in the manner illustrated in my application filed June 7, 1926, Serial No. 115,169, but in the present instance, terminates above the top of the extension member so that the case may be disposed horizontally, the closure 6 opened and the cover 16 of the container or receptacle likewise opened to permit access to its interior, in the manner of a suit case without disturbing the garments suspended from the hangers 11. The case may also be swung open, as illustrated in Figure 2, when the closure 6 serves to prevent overbalancing 35 thereof, and the container 13 removed and carried by its handle 28 when access may be had to the garments 11 in the manner of a conventional wardrobe trunk.

It will be thus apparent that I provide an 40 improved suit case type baggage carrier having provisions for carrying wardrobe and also similar articles of clothing and which has all the exterior appearances of a suit case and which further has a well or space at the 45 bottom into which the garments may extend and in which shoes, hats or other articles may be packed.

What I claim as my invention is:

1. In a baggage carrier of the character 50 described, a case, a closure for the case, an extension member projecting outwardly from the case at its bottom as a rigid structural unit thereof to provide an article receiving space extending into the closure when closed, and wardrobe means within the case.

2. In a baggage carrier of the character 60 described, a case, a closure for the case, an extension member projecting outwardly from the case at its bottom as a rigid structural unit thereof to provide an article receiving space extending into the closure when closed, wardrobe hanging means within the case, a movable container for various articles, and means securing the container in the case out- 65 wardly of the wardrobe hanging means.

3. In a baggage carrier of the character described, a case, a closure for the case, an extension member projecting outwardly from the case at its bottom as a rigid structural unit thereof to provide an article receiving 70 space extending into the closure when closed, wardrobe hanging means within the case, a movable container for various articles, and means securing the container in the case outwardly of the wardrobe hanging means, said 75 container having its forward portion in substantially the same plane as the forward portion of the extension member.

4. In a baggage carrier of the character described, a case, a closure for the case, an 80 extension member extended from the bottom of the case as a rigid structural unit thereof and into the closure, wardrobe means within the case, and a removable container for various articles secured in the case outwardly of the wardrobe means, said extension member projecting beyond the case a distance substantially equal to the depth of the closure and said container having its forward portion in substantially the same vertical plane as the forward portion of the extension member. 90

5. In a suit case type wardrobe carrier, a case, a hinged closure for the case, wardrobe means within the case, an extension member 95 projecting outwardly beyond the case from the lower portion thereof and forming an article receiving well extended into the closure when closed, and means spacing the walls of the extension member from the adjacent walls of the case and the closure to provide clearance, said means forming a rigid connection between said case and members. 100

6. In a suit case type wardrobe carrier, a 105 case, a hinged closure for the case, wardrobe means within the case, an extension member providing an article receiving well and projecting from the lower portion of the case as a rigid structural unit thereof and 110 extended into the closure when closed, and a reinforcing strip extending about the extension member inner end to space the walls thereof from the adjacent walls of the case and the closure to provide clearance. 115

7. In a suit case type wardrobe carrier, a case, a hinged closure for the case, wardrobe means within the case, an extension member providing an article receiving well and projecting from the lower portion of the case as 120 a rigid structural unit thereof and extended into the closure when closed, a reinforcing strip extending about the extension member inner end to space the walls thereof from the adjacent walls of the case and the closure to provide clearance, and a container removably secured in the case outwardly of the wardrobe means and over which the closure fits when closed. 125

8. In a suit case type wardrobe carrier, a 130

case, a hinged closure for the case, wardrobe means within the case, an extension member projecting from the lower portion of the case and extended into the closure when closed, a reinforcing strip extending about the extension member inner end to space the walls thereof from the adjacent walls of the case and the closure to provide clearance, and a container removably secured in the case outwardly of the wardrobe means and over which the closure fits when closed, the bottom of said container being disposed above the top of the extension member to provide a well in the extension member for receiving articles.

9. In a suit case type wardrobe carrier, a case, a hinged closure for the case, wardrobe means within the case, an extension member projecting from the lower portion of the case and extended into the closure when closed, a reinforcing strip extending about the extension member inner end to space the walls thereof from the adjacent walls of the case and the closure to provide clearance, a container removably secured in the case outwardly of the wardrobe means and over which the closure fits when closed, the bottom of said container being disposed above the

top of the extension member to provide a well in the extension for receiving articles, and a hinged cover for said container whereby access may be had to the interior thereof without removing it from the case when the case is disposed horizontally and opened.

10. In a suit case type wardrobe carrier, a case, a hinged closure therefor, wardrobe means in the case, and a box-like member having its top and rear walls open, said member being secured in the lower portion of the case to project into the closure when closed, the open side of the member being disposed internally of the case.

11. A wardrobe type suit case, comprising a wardrobe body having an open face, garment hanging means within the garment body, a lid hinged to close thereover, a removable article container supported in said suit case to close the major area of the open face of said body, and a filler member in the lower end of said body and rigid therewith between the bottom of said body and the bottom of said container, said filler member extending into the lid when closed.

In testimony whereof I hereunto affix my signature.

GEORGE HENRY WHEARY.
